(57) **CLAIM**

The ornamental design for a crossbar member to be included in a track belt for vehicle tires as shown and described.

DESCRIPTION

FIG. 1 is a right side perspective view from above of the crossbar member to be included in a track belt for vehicle tires showing my new design;

FIG. 2 is a right side perspective view from below of the crossbar member to be included in a track belt for vehicle tires of FIG. 1;

FIG. 3 is a front elevational view of the crossbar member to be included in a track belt for vehicle tires of FIGS. 1 and 2, the rear elevational view being substantially identical;

FIG. 4 is a right side elevational view of the crossbar member to be included in a track belt for vehicle tires of FIGS. 1-3, the left side elevational view being substantially identical;

FIG. 5 is a top plan view of the crossbar member to be included in a track belt for vehicle tires of FIGS. 1-4; and, FIG. 6 is a bottom plan view of the crossbar member to be included in a track belt for vehicle tires of FIGS. 1-5.

1 Claim, 6 Drawing Sheets
